R. K. CHASE.
FLUSH TANK VALVE.
APPLICATION FILED NOV. 20, 1916.

1,227,037.

Patented May 22, 1917.

UNITED STATES PATENT OFFICE.

RUDOLPH K. CHASE, OF SYRACUSE, NEW YORK.

FLUSH-TANK VALVE.

1,227,037.

Specification of Letters Patent. Patented May 22, 1917.

Application filed November 20, 1916. Serial No. 132,435.

To all whom it may concern:

Be it known that I, RUDOLPH K. CHASE, a citizen of the United States, residing at Syracuse, in the county of Onondaga and State of New York, have invented certain new and useful Improvements in Flush-Tank Valves, of which the following is a specification.

The present invention relates to water distribution and has particular reference to new and useful improvements in flush tank valves.

An object of my invention is to provide a valve of the class described which will be moved to closed position with the pressure, that is, in the direction in which the liquid is flowing so as to prevent leakage.

Another object of my invention is to provide a valve of the class described which is strong and durable, effective in operation, may be cheaply manufactured and installed and is capable of application to any standard flush tank without material alteration of the tank structure or the fixtures thereof.

Other objects and advantages of my improved valve not appearing in the foregoing will become apparent from the following detailed description and the claims, taken with an inspection of the accompanying drawing, in which:

Figure 1 is a longitudinal sectional view of a flush tank showing my improved valve applied thereto; and

Fig. 2 is an enlarged vertical sectional view of my improved valve.

Referring more particularly to the drawing, wherein similar characters of reference designate like and corresponding parts throughout the various views, 10 designates the tank, the same being provided with the usual side and end walls 11 and bottom 12.

My improved valve embodies an expansion chamber 13 provided with a threaded inlet collar 14, the inner peripheral margin of the outer end of said collar being beveled as at 15 to provide a valve seat. A conduit section 16 is provided, said section being mounted in the bottom 12 as at 17. An annular flange 18 adjacent the lower end of said conduit section serves to provide water-tight connection with the bottom 12. The upper end of the conduit section 16 is annularly enlarged as at 19 and internally threaded to engage the collar 14 as indicated at 20. The enlarged portion 19 forms a valve chamber in which a ball valve 21 is operable, said valve being

suspended from the lower end of a rod 22, said rod extending vertically through the chamber 13. The upper end of the chamber is formed with a concentric projection 23 provided with an aperture 24 in which the rod 22 is adapted to operate. The upper end of the rod 22 is enlarged and threaded as at 25 to receive a cap 26, said cap being in pivotal engagement with a rock arm 27, said rock arm having pivotal engagement as at 28 with a standard 29 mounted on the upper end of the casing 13.

A second standard 30 is mounted on the upper end of the chamber 13 at a point opposite the standard 29, a float rod 31 being pivoted at 32 in said standard 30. A link 33 affords connection between the free end of the rock arm 27 and said float rod 31. The float rod is jointed as at 34 so that the sections thereof may be adjustably arranged to change the interval of operation of the float. The float is designated 35 and is carried by the free ends of the rod 31.

A discharge elbow 36 is formed integrally with the chamber 13 and opens downwardly, a conduit section 37 being in threaded engagement with the lower end of said elbow. Preferably, the free end of the conduit section 37 should extend to a point below the lowest level of liquid in the tank, so that in operation the device will be practically noiseless and there will be no danger of splashing as now often occurs.

In operation the float 35, of course, will always follow the liquid level in the tank 10. A liquid supply conduit (not shown) is to be connected to the lower end of the conduit section 16, the direction of flow being upwardly through said conduit section. In operation, assuming that the tank is empty, the float 35 will be in the lowermost position and the valve 21 open.

As the liquid flows upwardly through the conduit section 16 the expansion chamber 100 will become filled and the liquid pass outwardly through the elbow 36 and conduit section 37 to replenish the tank. As the float rises with the liquid level in the tank the rod 31, through the link 33 will act upon the rock arm 27 to raise the rod 22 thereby bringing the ball valve 21 into engagement with its seat 15. Of course, the valve is not entirely closed until the required height of water level is reached. The height of liquid 110 level and consequently the amount of liquid deposited in the tank can be regulated by

the angular relation of the sections of the float rod 31.

I desire to lay particular stress upon the arrangement of valve, particularly in that the same is moved to closed position with the direction of flow instead of against the direction of flow as is now common. This tends to reduce the leakage and relieve strain upon the valve rod, float rod and the rock arm 27 and link 33. The only conditions under which strain exists is when the valve is open which would be only temporarily. It will also be apparent that the device may be quickly and easily installed in any flush tank without altering the structure of the tank or changing the pipe connections or fixtures in use therewith. The float rod can assume the positions ordinarily taken by the float rods now in use and will not consume more space than the standard float rod and float. I desire to point out that the standard 29 as shown projects above the float rod in order to assist in guiding and reinforcing the same during operation. From the above description taken in connection with the accompanying drawing, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:

1. A valve comprising a body having an expansion chamber, said chamber being pro-

vided with a valve seat on the lower end thereof, a conduit connecting the lower end of said chamber with a source of liquid supply, a concentric projection having an aperture therein provided on said chamber, a rod operable through said chamber and aperture having a valve on the lower end thereof to engage said seat, a standard mounted on the upper end of said casing, a rock arm pivotally connected to said rod midway its ends, one end being in pivoted engagement with said standard, a second standard mounted on said chamber opposite the first said standard, a float, an adjustable float rod having one end connected to the float and the opposite end connected to the second standard, and a link pivotally engaged with said float arm and the other end pivotally connected with the free end of the rock arm.

2. A valve comprising a body having an expansion chamber and an inlet opening through its lower end, said chamber being provided with a flange surrounding said opening having a valve seat, a conduit connecting said flange with a source of liquid supply, a valve rod operable vertically through said chamber and having a ball on the lower end thereof to engage said seat, a float rod and float, said rod being pivoted upon the upper end of said chamber, a rock arm pivoted to the chamber, a link connecting said rock arm with said float rod, said rock arm being connected with the upper end of said valve rod, and an outlet for said chamber.

In testimony whereof, I affix my signature hereto.

RUDOLPH K. CHASE.
